UNITED STATES PATENT OFFICE.

HERMANN DEPPERMAN, OF NOWAWES-NEUENDORF, GERMANY.

METHOD OF COVERING THREAD-BUTTONS.

1,269,402.

Specification of Letters Patent. Patented June 11, 1918.

Original application filed May 13, 1913, Serial No. 767,464. Divided and this application filed March 30, 1915. Serial No. 18,179.

To all whom it may concern:

Be it known that I, HERMANN DEPPERMAN, a subject of the Emperor of Germany, residing in Nowawes-Neuendorf, Germany, have invented certain new and useful improvements in Methods of Covering Thread-Buttons, of which the following is a specification.

This invention relates to a method for covering buttons and particularly for covering buttons with thread.

The main objects of the invention are to contrive a method for covering buttons which can be entirely performed by machine; in which there are but three principal steps; by which a particularly artistic button is quickly produced; by which a durable covering is produced, by which those parts of a button covering which are subjected to the most wear are in the natural course of the method covered with the most thread; and which can be performed at low cost of manufacture.

These and other features, capabilities and advantages of the invention will appear in the subjoined detailed description of one specific embodiment thereof, the product of which is illustrated in the accompanying drawings in which—

Figures 1, 2 and 3 are plan views of the button in actual size, Fig. 1 illustrating the button after it has been subjected to the first principal step; Fig. 2 illustrating the button after it has been subjected to the second principal step; and Fig. 3 illustrating the completed button after it has been subjected to all three principal steps and is ready for the market.

Figs. 4, 5 and 6 are enlarged plan views of the button corresponding to Figs. 1, 2 and 3 respectively.

Fig. 7 illustrates a fragmental enlarged plan view showing a portion of the intermediate weft.

This application is a divisional application of my patent application Serial No. 767,464, filed May 13, 1913.

As illustrated in Figs. 1 and 4, a foundation ring 1 composed of metal or other suitable material is covered with the thread 2 which is wound transversely of the annular portion of the ring member, that is, wound around said annular portion whereby a securing surface is formed on said ring 55 for the thread winding of the next step.

When the annular portion has been completely covered in this manner, the resulting thread-covered ring is ready for the next step.

Preferably the same thread 2 may be used for the second principal step, without cutting off such thread after having finished the first step. The second principal step consists in winding the thread, as 2', around the covered ring diametrically of said ring, 65 that is, diametrically of the disk outline formed by said ring into a star-like warp so that the threads which constitute such warp will cross each other at the center of the ring as illustrated in Figs. 2 and 5. By 70 this covering, it will be seen that, not only is the button produced, but the ring or edge of the button, which will be subjected to the greater wear, receives two coverings of thread. The foregoing main steps are pref- 75 erably performed by machine and can be conveniently performed by the machine disclosed in my patent application Serial No. 767,464, filed May 13, 1913, of which this application is a divisional application. 80

The next and last principal step is preferably performed on a tambour machine. In this last step the button, after having been covered by two layers of thread in the first two steps, is provided with an intermediate weft in which a thread 3 is interwoven between the diametrically extending portions of the thread 2' to secure the same in position, the thread being illustrated, (Figs. 3 and 6) in the present instance, as 85 forming a complete circle which is the line that is a circle concentric with the ring 1 and intermediate the center of said ring and the periphery of said ring. By this last weft, the crossing threads of the star-like 90 warp produced by the second principal step are firmly secured in position.

This intermediate weft formed by the thread 3 is clearly illustrated in Fig. 7, in which the thread 3 is shown (going from 100 right to left) as forming a knot having a portion *a* passing under one of the diametrically extending portions of the thread 2', then forming a loop *b*, from which its portion *c* again passes under said diametrically 105 extending portion of the thread 2', then turns so that its portion *d* passes over such diametrically extending portion, whereupon it passes through the loop *b* after which it passes on to form a similar knot on the 110

next diametrically extending portion of the thread 2.

Forming this knot however the portion *c* returns not only under the diametrically extending portion, but also through the foregoing loop *b*. All the following knots are formed similarly as the second one, until the intermediate weft is finished.

The method consists essentially of three principal steps but obviously these can be departed from in certain respects as for instance by omission and addition, without departing from the general scope of the invention, as defined by the appended claims.

15 I claim:

1. The method of manufacturing thread buttons which consists in taking a foundation ring, winding thread around the annular portion of said ring whereby a securing surface is formed for the thread winding of

the next step, and then winding thread diametrically of the circular disk outline formed by said ring, whereby the peripheral edge of said ring receives two covers.

2. The method for the manufacture of 25 thread buttons which consists first, in taking a foundation ring, winding thread around the annular portion of said ring whereby a securing surface is formed for the thread winding of the next step, then winding 30 thread diametrically of the circular disk outline formed by said ring whereby the peripheral edge of said ring receives two covers, and then interweaving thread between the threads of the diametrical warp to secure 35 the same in position and to one another.

HERMANN DEPPERMAN.
